Primary Examiner — Cynthia M Chin(74) *Attorney, Agent, or Firm* — Winthrop & Weinstine, P.A.(57) **CLAIM**

The ornamental design for a pontoon boat with cuddy cabin, as shown and described.

DESCRIPTION

FIG. 1 is a perspective and partially disassembled view of a pontoon boat with cuddy cabin;

FIG. 2 is a perspective view of the pontoon boat with cuddy cabin of FIG. 1 as viewed from underneath;

FIG. 3 is a perspective view of a cuddy cabin section of the pontoon boat with cuddy cabin of FIG. 1, shown separately for the clarity of illustration;

FIG. 4 is a top view of FIG. 3;

FIG. 5 is a bottom view of FIG. 3;

FIG. 6 is a right side view of FIG. 3;

FIG. 7 is a left side view of FIG. 3;

FIG. 8 is a front view of FIG. 3;

FIG. 9 is a rear view of FIG. 3;

FIG. 10 is a perspective view of the deck of the pontoon boat illustrated in FIG. 1, shown separately for the clarity of illustration; and,

FIG. 11 is a top view of FIG. 10.
